[57] CLAIM

The ornamental design for a bench, as shown and described.

DESCRIPTION

FIG. 1 is a front side isometric view of a bench, showing my new design;

FIG. 2 is a top plan view thereof;

FIG. 3 is a front elevational view thereof;

FIG. 4 is a bottom plan view thereof;

FIG. 5 is a back elevational view thereof;

FIG. 6 is a right side elevational view thereof; and,

FIG. 7 is a left side elevational view thereof.

The broken line illustration in the drawings is not part of the design sought to be patented.

FIG. 1 has been shown on a reduced scale.
